ATTORNEY

UNITED STATES PATENT OFFICE

OLIVER BURNSIDE ANDREWS, OF CHATTANOOGA, TENNESSEE

CONTAINER

Application filed November 21, 1929. Serial No. 408,705.

This invention relates to containers, and more particularly to fiber containers of large size which are adapted for carrying bulky articles, such as loaves of bread and which may be folded into compact form and used a plurality of times.

The invention provides a relatively simple, dependable, highly efficient and convenient container which may be cheaply produced and used a plurality of times. Various features and advantages will appear from a detailed description given below taken in connection with the accompanying drawings which form a part of this specification and illustrate merely by way of example an embodiment of the device.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a perspective view of the container;

Fig. 2 is a horizontal section taken on the line 2—2 of Fig. 3;

Fig. 3 is a vertical section of the container taken on the line 3—3 of Fig. 2;

Fig. 4 is a perspective view of a modified form of the container;

Fig. 5 is an enlarged sectional view of the hinge showing the cover in closed position; and

Fig. 6 is an enlarged sectional view of the hinge showing the cover in wide open position.

Like reference characters denote like parts in the several figures of the drawings.

In the following description and in the claims parts will be identified by specific names for convenience, but they are intended

to be as generic in their application to similar parts as the art will permit.

The present invention provides a container which is preferably formed of stiff fiber board impregnated with a waterproofing material, such as a paraffin solution. The fiber board may be impregnated with this material on both sides whereby rigidity of the fiber board is increased and deterioration due to moisture and other causes may be substantially eliminated.

The invention is shown as applied to a container formed of fiber board treated in the above manner which comprises side members 10 which are suitably scored and bent into rectangular form and secured as by stitches 11. Top and bottom closure members 12 are provided with a flange 14 which is secured to side members 10 in any suitable manner as by stitches 15. Side members 12 are secured to opposite sides of the container and are of such dimension that when folded back upon the container they do not project beyond said side members. They are accordingly especially adapted for use in a container in which the width is not over twice the depth. It is obvious that if the width is equal or less than the depth a single top or bottom member could be employed which would extend entirely across the container, instead of the two members illustrated in the drawings.

Members 12 are deeply scored from both surfaces as shown in Figs. 5 and 6 to form a hinge and an extra parallel score is made on the outside adjacent the hinge score whereby they may be bent both ways without injury and may be bent back upon themselves to lie flat on the outer surface of the container. This is particularly important when extremely heavy fiber board is employed in order to prevent cracking due to repeated bending. Members 12 are provided with a plurality of eyelets 16 through which a fastening means such as tape, twine or light soft wire, (not shown) may be threaded for securing the container in closed position.

Side flaps 20 are formed with flange members 21 which are stitched to sides 10 of the container in a manner similar to flanges 14. Members 20 are also deeply scored on both

sides, and provided with an extra outside score similar to members 12 so that they may be folded interiorly of the container to complete the closure and to prevent dirt and other materials from entering the same and may also be folded back upon the outer surface of the container. When both the members 12 and 20 are thus folded back the container may be collapsed and shipped in a flat condition.

10 This feature is of particular importance where the box is to be returned for reuse. It may be readily assembled, however, by folding these members interiorly thereof and passing a suitable securing means through 15 eyelets 16. The flanges 14 and 21 provide strengthening means around the entire top and bottom edges of sides 10.

In the modified form of container shown in Fig. 4, members 20 are omitted and side 20 member 10 is provided with an eyelet 25 in substantial alignment with eyelets 16 of members 12. In this type of container members 12 may be secured in closed position by passing a tape (not shown) through eyelets 16 25 and 25. Top and bottom members 12 in the form shown in Figs. 1 and 4 are preferably made sufficiently wide to project over the sides 10 by which they are supported. This prevents the container from crushing and 30 thereby injuring the articles carried therein.

Containers of the above type have been formed in large sizes, as for example, 3 ft. square, out of heavy fiber board which are impregnated with a paraffin solution and 35 were found to be sufficiently rigid to be used in the distribution of light articles, after which they were collapsed and returned for further use. The scoring of the top and bottom members prevents damage from repeated 40 folding and the waterproof surface of the fiber board prevents injury and deterioration from moisture and from repeated handling.

While certain novel features of the invention have been shown and described and are 45 pointed out in the annexed claims, it will be understood that various omissions, substitutions and changes in the forms and details of the device illustrated and in its operation may be made by those skilled in the art without departing from the spirit of the invention.

What is claimed is:

1. A container of waterproof fiber board comprising a side member formed from a 55 strip of said fiber board, suitably scored and bent to form the sides of said container, top and bottom members of heavy waterproof fiber board deeply scored on both sides to form a hinge, an extra outside score adjacent 60 and parallel to said hinge to permit said members to be folded outwardly against said side.

2. A container of waterproof fiber board comprising a side member formed from a 65 strip of said fiber board, suitably scored and

bent to form the sides of said container, top and bottom members of heavy waterproof fiber board deeply scored on both sides to form a hinge, a flange adjacent said hinge, means for securing said flange to the outer surface of said side members whereby said top and bottom members may be folded inwardly as a closure for said container and may be folded outwardly against the surface thereof when said container is collapsed, and 75 additional members deeply scored to provide a hinge and having a flange secured to the opposite faces of said container to close the openings between the edge of said top and bottom members and the side of said container when said container is closed, said top and bottom members and said additional members having an extra score parallel to said hinge scores to facilitate said members in bending outwardly against the sides of 80 said container.

In testimony whereof I have hereunto set my hand.

OLIVER BURNSIDE ANDREWS.
